MECHANICAL COIN CHANGER

Joseph E. Hagstrom, Kansas City, Mo., assignor
to C. Earl Hovey, trustee, Kansas City, Mo.

Application October 2, 1940, Serial No. 359,365

16 Claims.

(Cl. 194—80)

This invention relates to mechanical coin changers of the type employing coin controlled means for manually manipulating the parts thereof after the coin to be changed has been dropped into the machine, and the primary aim is to provide such equipment wherein coins of like denominations are carried in a random condition in a specially designed hopper, from which the same are transferred and disposed in order for ejecting the proper number thereof.

This invention has for one of its important aims the provision of a coin changer of the aforementioned character wherein is provided unique, novel and efficient mechanism for arranging coins in edge-to-edge positions in a relatively narrow feed chamber and all in a common plane, after said coins have been dumped into the hopper of the machine in a random condition and without regard to their relative positions.

A yet further aim of this invention is to provide a coin changer capable of receiving a coin of either one or two denominations and upon manual manipulation of the ejecting means, delivering the proper change for the coin inserted, all through the employment of rugged, inexpensive and compact apparatus.

More specifically, it is one of the prime objects of the instant invention to produce a mechanical coin changer capable of quickly and positively ejecting therefrom, two nickels when a dime has been inserted, and five nickels when a quarter has been introduced into the machine.

A yet further object of this invention is the provision of coin handling equipment of the aforesaid type having manually controlled coin ejecting means, one element of which moves through a path of travel of fixed length, while another element thereof travels through at least two paths, the lengths of which are different, to the end that different numbers of coins are ejected from the machine when the second mentioned element travels through its paths of different length.

A still further object of this invention is to provide a coin changer with coin controlled means for rejecting "slugs" or the like, which coin controlled means are of conventional character but cooperate with the unique parts embodying this invention, in a manner to insure the owner of the machine against loss.

Because a mechanical coin changing machine that serves the public must be inconspicuous, compact easy to operate and speedy in its function, this invention contemplates the employment of specially formed parts, all of which cooperate to fulfill such specification. Minor objects of the invention therefore, will become apparent when the manner of building a coin changer in accordance with the broader concepts of the invention is understood.

One embodiment of the invention is illustrated in the accompanying drawings, wherein:

Figure 1 is a front elevational view of a mechanical coin changer made in accordance with the present invention.

Fig. 2 is a horizontal sectional view through the same taken on line II—II of Fig. 1.

Fig. 3 is a side elevational view of the rear wall structure only.

10 Fig. 4 is a fragmentary elevational view of the lower portion of the partition.

Fig. 5 is a vertical cross sectional view taken on line V—V of Fig. 1.

15 Fig. 6 is a fragmentary detailed sectional view taken on line VI—VI of Fig. 5.

Fig. 7 is a perspective view of the upper coin carrying plate entirely removed from the operative position.

20 Fig. 8 is a similar view of the lower coin carrying plate.

Fig. 9 is a fragmentary detailed elevational view of the rear face of the arcuate rack and some of the parts associated therewith.

25 Fig. 10 is a top plan view of the parts detailed in Fig. 9; and

Fig. 11 is a detailed vertical sectional view taken on line XI—XI of Fig. 5.

The case appropriately formed to house all of the parts of the coin changer, has a removable cover 12 having a hole 14 in the front wall thereof, in communication with a delivery stall 16.

30 A rear wall 18 has a peripheral flange 20 formed thereon and carries partition 22 in spaced relation with the inner face thereof to establish a feed chamber, generally designated by the numeral 24. This feed chamber has an upper portion behind the reciprocable slide 60 that is in communication with a lower portion in the form of a continuous coin passage 28 extending from the upper portion to window 30 where the coins fall into delivery stall 16.

35 A deflector 32 extending outwardly through window 30 into delivery stall 16, insures effective escape of coins 34. Coin passage 28 is established by the use of filler strips 36 fastened directly to the inner side of wall 18, as illustrated in Fig. 3. These filler strips 36 are arranged to form a coin passage 28 that has a vertical stretch 38, an offset inclined stretch 40, and another inclined section 42.

40 A retaining finger 44 at the zone of juncture between inclined stretch 40 and inclined section 42, is pivoted to wall 18 by screw 46 and yieldably held by spring 48 where coins 34 will not move into inclined section 42 for passage outwardly through window 30 until reciprocating ejector element 50 forces coins 34 past the end of finger 44. Ejector element 50 is operated by connection to parts hereinafter to be described.

45 50 55 60 Partition 22 is inclined upwardly and forward-

ly near the top of wall 18 forming a part of the case, to establish a coin hopper 52, the ends of which are closed by sheets of material forming walls 54, each flanged as at 56 for attachment to spacers 58 on wall 18. Hopper 52 merges with the relatively wide upper portion of feed chamber 24, the cross sectional dimension of which is great enough to receive slide 60 and coins 34. Slide 60 has an inclined or beveled upper edge 62 for the purpose of tipping the coins toward the space between wall 18 and its inner surface.

Slide 60 moves to and from the position shown in Fig. 5 and in so doing, agitates and collects the coins from within hopper 52 and moves the same to a place between its inner face and wall 18 where they rest upon rockable floor member 64 pivoted intermediate its ends as at 66, directly to slide 60. The outer faces of spacers 58 and the vertical filler strip 36 along one side of vertical stretch 38, forming a part of coin passage 28, are in the same plane as the outer face of slide 60, to the end that the said outer face of slide 60 will ride against the inner face of partition 22 along the relatively wide part of coin passage 28.

On the back side of slide 60 and between wall 18 and said side, is disposed a boss 68 and a pivoted strip 70 having a lateral leg 72. A spring 74 yieldably urges strip 70 to the position shown in Fig. 3. Another spring 76 mounted on boss 68 yieldably maintains one end of rockable floor member 64 against shoulder 78. A stop 80 riveted to the back of slide 60 serves as a part to limit the movement of both member 64 and strip 70. Lateral leg 72 enters coin passage 28 through gap 82 when slide 60 is at the lower end of its vertical path of travel.

A coin chute 84 of special design, permits the use of two slug rejectors 86 and 88 of well-known design. These rejectors insure that only genuine coins (in this instance, a dime and a quarter), will pass to the hereinafter described manually operable coin controlled means for dispensing the correct number of coins 34.

A swingable frame 90 forms a part of such rejectors 86 and 88 and to adapt two of such elements to this machine, simultaneous operation of frame 90 is procured by joining together the operating mechanism for frame 90 through the medium of a yoke 92. Wire 94 joins yoke 92 with one end of beam 96, the other end of which is inclined downwardly and outwardly from a pivotal connection 98 and into the path of travel of walls 100 and 102 on upper and lower plates 104 and 106 respectively. This beam 96, as well as the other parts of the mechanism, is supported by frame 108 secured either to partition 22 or end walls 54.

Part of frame 108 journals drive shaft 110 disposed transversely and maintained in a set position by spring 112, one end of which is secured to shaft 110, while the other end thereof bears against a part of frame 108. This conventional construction insures that shaft 110 will be retrieved to cause the associated parts to remain in a set condition.

A segmental plate in the nature of an arcuate rack 114, is mounted upon the inner end of shaft 110. Teeth 116 on rack 114 engage dog 118 pivotally mounted upon frame 108 and inclined in the normal position by spring 111. The interrelation of dog 118 and teeth 116 is well-known to be that of precluding return of rack 114 to a point of beginning after it has once been moved far enough to engage dog 118. When rack 114

has been carried completely to the end of its path of travel, dog 118 will have passed teeth 116 and the return action is permitted. Thus, all of the parts operated by rack 114 are protected against accidental movement in a rearward direction after the operation has been started.

A stop 120 engages the edges of rack 114 to limit the action of spring 112 and to limit the movement imparted thereto by the operator. 10 Such movement is established through the medium of an operating handle 122 journaled in cover 12 and provided with an arm 124 that carries pin 126 to engage a notch 128 in arm 130 pinned to shaft 110. Stops 132 on cover 12 limit the movement of arm 124 to substantially 180° arc. Through such arrangement of parts, cover 12 may be moved to and from its place over the mechanism. Obviously any manually operable structure for turning shaft 110 may be employed.

20 Rack 114 has one end of link 134 pivotally attached thereto to one side of its axis of rotation as at 136, while the other end of said link is fastened to slide 60 by shouldered machine-screw or the like 137 that passes through opening 138 provided through partition 22 for the purpose.

25 A connecting arm 140 is likewise operated by rack 114. Arm 140 has one end pivotally attached to rack 114 by element 142, while the other end thereof is pivotally secured to wall 102 of lower carrying plate 106 in a manner illustrated in detail in Fig. 8. Thus, as will be more fully hereinafter set down, oscillation of rack 114 about its axis by shaft 110 will reciprocate both slide 60 and plate 106 through paths of travel of established lengths.

30 35 Upper coin carrying plate 104 is in superimposed relation with respect to lower plate 106. A connecting arm 144 is pivotally connected to plate 104 by bolt 146 at its one end, and pivotally joined to bar 148 at its other end. The point of connection on bar 148 between arm 144 and said bar is intermediate the ends of the latter for the purpose of swinging the bar about a pivot pin 150. Bar 148 is slotted at the end opposite to pin 150 and this slot 152 receives a pintle 154 on the ejector element 50. This pintle 154 enters hole 156, shown clearly in Fig. 3.

40 45 Lower coin carrying plate 106 has a slot 158 and a relatively long slot 160 formed there-through in register with slots 162 and 164 respectively of plate 104. Plate 104 has skirts 166 and 168 thereon around at least a part of slots 162 and 164 respectively, while plate 106 has like skirts 170 and 172 around its slots 158 and 160 respectively. As illustrated in Fig. 5, the lowermost edges of skirts 170 and 172 ride along the surface of a specially formed track 174 which slidably carries both plates 104 and 106. This track extends over the open top of a coin box 176 which receives the coin introduced into the machine by the operator as the change therefor, in the form of the correct number of coins 34, is delivered into stall 16. An opening 178 through the bottom of track 174 allows the coin being changed to drop into box 176.

50 55 The coin 180, illustrated in Fig. 6, is a quarter, while the coin 182, shown in Fig. 11, is a dime—the latter being in slots 160 and 164, while the former is in slots 158 and 162. Ear 184 on connecting arm 140 engages retaining finger 44 after a certain number of coins have been fed from inclined stretch 40 by ejector element 50, in a way more definitely set down in the description of the operation of the machine.

60 65 70 75 Dog 186 mounted on a part of frame 108 lies

in the path of travel of wall 102 of lower plate 106. When this wall 102 strikes dog 186 to one side of its pivotal connection 188, the end thereof opposite to pivotal connection 188, is moved inwardly into the path of travel of wall 100 of plate 104 to preclude further travel. Spring 190 yieldably maintains dog 186 in the normal position against stop 192, shown in Fig. 10.

The means provided for barring the introduction of a coin to be changed when there is an insufficient number of coins 34 to make the change, comprises a gate 194 pivotally mounted to the upper part of coin chute 84 as at 196. This gate has laterally extending head 198 and an inclined laterally projecting wall 200. Head and wall 198 and 200 respectively, enter coin chute 84 through openings provided in the side thereof for the purpose and only one of said parts (198 or 200) may be in the path of travel of a coin entering chute 84 at a time.

Spring 202 yieldably holds gate 194 in a position where either head 198 or wall 200 is in a position within coin chute 84. A rod 204 reciprocably journaled in bearing 206 has one end close to gate 194 at its lower end. The other end of rod 204 is fastened to one end of rocker 208 pivotally mounted as at 210 to the underside of that part of partition 22 forming hopper 52. The other end of rocker 208 engages wire 212 slidably journaled in lug 214 and circumscribed by a spring 216 extending between cross pin 218, wire 212 and lug 214 for the purpose of yieldably holding rod 204, rocker 208 and wire 212 in a normal position with finger 220 at the lower end of a vertical path of travel. This finger extends into feed chamber 24 to be engaged by strip 70 so long as leg 72 thereof strikes a coin 34 in coin passage 28 when slide 60 is at the lower end of its path of travel. Thus, if there is sufficient number of coins 34 in the inclined stretch 40 of coin passage 28, the striking of finger 220 by strip 70 will operate parts 212, 208 and 204 to push the lower end of gate 194 to the position shown in Fig. 5. Either a coin 189 or 182 may then thereafter be inserted to be changed. On the other hand, if there is no coin 34 below gap 82 to engage leg 72 and position strip 70 to strike finger 220, gate 194 will remain in a position where head 198 thereof is barring the entrance of a coin into chute 84.

As a coin passes inclined wall 200, head 198 is forced into coin chute 84 there to remain until released, as just described. Coin chute 84 is specially made to receive for direction, either a quarter or a dime to slug rejectors 86 and 88 respectively.

Inturned flanges 222 at the zone of juncture between branch 224 of coin chute 84 and that part extending to rejector 88, have their proximal free edges a distance apart greater than the diameter of the dime 182. Thus, through the action of gravity the dime will drop between flanges 222 and into rejector 88. A quarter will engage flanges 222 and be diverted into rejector 86. If a slug should be dropped into the machine, it will be held in rejectors 86 or 88, as the case may be, until frame 90 is operated to drop the same through conduit 225 that extends from a point below both rejectors 86 and 88 to stall 16.

The operation of frame 90 occurs when operating handle 122 is turned to move lower plate 106 to the position shown in dotted lines of either Figs. 6 or 11. When in such position, the inclined edge of beam 96 will be struck by wall 102

and yoke 92 will be drawn down by wire 94 to operate the aforesaid conventional parts of the rejector, inclining frame 90 to release the slug that has been held against entrance into the slots of the plates by the rejector parts.

Assuming now that hopper 52 is filled with nickels 34 and that there is a continuous supply of said nickels in coin passage 28 extending from finger 44 around to that space in feed chamber 24 above floor member 64. The operator desires two nickels for a dime and proceeds to introduce the dime into coin chute 84, thereby moving gate 194, as above mentioned.

The dime passes through rejector 88 and is dropped into registering slots 160 and 164 in plates 106 and 104 respectively (see Fig. 11). Operating handle 122 is now turned to draw lower plate 106 toward the position shown in dotted lines of the said figure, through the medium of arm 140 operatively attached to rack 114 on shaft 110 that is being rotated by handle 122. After plate 106 has carried dime 182 to a point where it strikes the end of slot 164 in upper plate 104, movement of this plate 104 is started to draw ejector element 50 to the left, as viewed in Fig. 3. Such movement is imparted to ejector 50 through the medium of arm 144, and bar 143. Movement of the mechanism to a place where it is arrested by stop 120 brings dime 182 over coin box 176 and causes ejector 50 to force two nickels 34 into inclined section 42 and past retaining finger 44. The two nickels travel through window 39 and into delivery stall 16. The force imparted to the string of nickels 34 in inclined stretch 40 by ejector 50 is sufficient to flex spring 48, but after two nickels have been so fed, ear 184 will move to a position behind finger 44 to preclude its permitting the passage of additional nickels to section 42. Releasing handle 122 will permit dime 182 to drop into coin box 176 and spring 112 will return all of the parts to the normal point of beginning. The manner in which dog 118 precludes accidental return to a point of beginning has heretofore been made clear. Likewise the manner in which strip 70 actuates gate 194 to set the same in the condition illustrated in Fig. 5, has been described.

When lower plate 106 has reached the position shown in dotted lines in Fig. 11, dog 186 will be moved to position one end thereof in front of wall 100 of upper coin carrying plate, to insure that said plate will not move beyond that position shown in dotted lines of Fig. 11.

Assuming that there is a sufficient supply of nickels 34 to change a quarter, which will always be the case if finger 72 has engaged a nickel below gap 82, a quarter may now be introduced into the changer. The quarter will drop through rejector 86 and into the position shown in Fig. 6 where it is within registered slots 158 and 162 of plates 106 and 104 respectively. Manipulation of handle 122 to move lower plate 106 to the left, as viewed in Fig. 6, will move quarter 180 against the end of slot 162 whereupon both lower and upper plates 106 and 104 will be moved toward the position shown in dotted lines of Fig. 6. So moving upper plate 104 will, as before mentioned, move ejector element 50 to the left, as seen in Fig. 3, a distance sufficient to force five nickels 34 into the inclined section 42 of coin passage 28. When said number of nickels has been allowed to fall by gravity into delivery stall 16, retaining finger 44 will be held against movement to a place where additional coins may escape from inclined stretch 40 by ear 184 assum-

ing the position shown in dotted lines of Fig. 6. When the operator releases his hold upon handle 122, quarter 180 will drop into coin box 176 and the parts will be returned to the normal position at their points of beginning by spring 112.

Each time nickels are fed by the introduction of coins, as just described, slide 60 will be reciprocated because of its connection with arcuate rack 114 by way of link 134. As slide 60 is reciprocated, the nickels will be moved into feed chamber 24 and arranged in edge-to-edge relation in a common plane with rockable floor member 64. When in the normal position, said member 64 will be inclined, as seen in Fig. 3, to maintain coin passage 28 always completely filled with nickels 34. When supplying the machine with nickels, hopper 52 may be filled with the same by merely dumping a quantity thereinto at random without regard to their relation to each other nor any order. It has been found by actually operating a machine made precisely as illustrated, that the nickels will enter feed chamber 24 without jamming and maintain a constant supply of coins 34 in the entire stretch of coin passage 28.

Equipment as disclosed hereby is particularly useful in locations where change is needed to operate vending machines, parking meters, turnstiles, and other coin controlled apparatus, and where it is possible to provide an inexpensive, durable and efficient mechanical changer, it is commercially practicable to use a large number thereof to stimulate sales or the operation of the aforesaid coin controlled equipment.

The illustrated embodiment of this invention exemplifies but one way of making a mechanical coin changer to embody the concepts of this invention, and it is obvious that one skilled in the art may deviate from details in construction without departing from the spirit of the invention or scope of the appended claims.

Having thus described the invention, what is claimed as new and desired to be secured by Letters Patent is:

1. In a mechanical coin changer of the character described, a case having a narrow vertical feed chamber formed to hold coins in edge-to-edge relation and in the same plane; a hopper for coins to be dispensed, said coins when in the hopper being in random condition; coin controlled means for ejecting coins from the feed chamber; and apparatus for transferring coins from the hopper to said feed chamber and simultaneously arranging the transferred coins in said edge-to-edge relation, said feed chamber being in a vertical plane and provided with a rockable floor movable by the ejecting means for rolling the coins from one portion of the feed chamber to another portion thereof, said ejecting means including an element for forcing a given number of coins from said last mentioned portion thereof.

2. In a mechanical coin changer of the character described, a case having a narrow vertical feed chamber formed to hold coins in edge-to-edge relation and in the same plane; a hopper for coins to be dispensed, said coins when in the hopper being in random condition; coin controlled means for ejecting coins from the feed chamber; and apparatus for transferring coins from the hopper to said feed chamber and simultaneously arranging the transferred coins in said edge-to-edge relation, said feed chamber being in a vertical plane and provided with a rockable floor movable by the ejecting means for

rolling the coins from one portion of the feed chamber to another portion thereof, said ejecting means including an element for forcing a given number of coins from said last mentioned portion thereof, said element being operated by the said ejecting means.

3. In a mechanical coin changer of the character described, a case having a narrow vertical feed chamber formed to hold coins in edge-to-edge relation and in the same plane; a hopper for coins to be dispensed, said coins when in the hopper being in random condition; coin controlled means for ejecting coins from the feed chamber; and apparatus for transferring coins from the hopper to said feed chamber and simultaneously arranging the transferred coins in said edge-to-edge relation, said feed chamber being in a vertical plane and provided with a rockable floor movable by the ejecting means for rolling the coins from one portion of the feed chamber to another portion thereof, said ejecting means including an element for forcing a given number of coins from said last mentioned portion thereof, said element being operated by the said ejecting means, the number of coins forced from the last mentioned portion of the feed chamber being governed by the denomination of the coin introduced into the coin controlled means.

30 4. In a mechanical coin changer of the character described, a case having a feed chamber formed therein; a hopper for coins to be dispensed; a vertical reciprocable slide in spaced relation to one side of the feed chamber; a rockable floor member on the slide between the slide and said side of the feed chamber; means for reciprocating the slide as the machine is operated; and means for tilting the floor member to move the coins along the feed chamber when the slide is at one end of its path of travel.

35 5. In a mechanical coin changer of the character described, a case having a feed chamber formed therein; a hopper for coins to be dispensed; coin controlled means for ejecting coins from the feed chamber; a vertical reciprocable slide in spaced relation to one side of the feed chamber; a rockable floor member on the slide between the slide and said side of the feed chamber; means for reciprocating the slide as the coins are ejected from the feed chamber; and means for tilting the floor member to move the coins along the feed chamber when the slide is at one end of its path of travel, there being a gate movable to a position precluding the introduction of a coin to the coin controlled means by a part of said slide when coins are not occupying a part of the said feed chamber.

60 6. In a mechanical coin changer of the character described, a case having a feed chamber and a coin passage formed therein; a hopper for coins to be dispensed, said coins when in the hopper being in a random condition; coin controlled means for ejecting coins from the coin passage; and means for arranging the coins being dispensed in edge-to-edge, vertical positions in a common plane and transferring the same from the hopper to the feed chamber and said coin passage, said means for ejecting the coins from said coin passage having an element movable to force a predetermined number of coins from the said passage, there being a retaining finger for precluding the discharge of more than said predetermined number of coins from the passage after the said number of coins has been ejected.

7. In a mechanical coin changer of the character described having a coin passage for the coins being dispensed and a coin chute to receive the coins to be changed, a gate movable to and from a position closing the coin chute, a finger in the coin passage provided with connections to the gate for moving the same upon actuation of the finger, and means for actuating the finger to close the gate when less than a predetermined number of coins are in the coin passage.

8. In a mechanical coin changer of the character described, a case having a coin passage formed therein arranged to hold a string of coins in edge-to-edge relation in a common plane, said coin passage having a length thereof designed to hold a predetermined number of coins equal in total value to the coin to be changed; an ejector element movable longitudinally throughout said length of the coin passage for forcing the coins from the said length of the coin passage; and means rendered operative by the introduction into the coin chute of the coin to be changed for moving the ejector element.

9. In a mechanical coin changer of the character described, a case having a coin passage formed therein arranged to hold a string of coins in edge-to-edge relation in a common plane, said coin passage having a length thereof designed to hold a predetermined number of coins equal in total value to the coin to be changed; an ejector element for forcing the coins from the said length of the coin passage; and means rendered operative by the introduction into the coin chute of the coin to be changed for moving the ejector element, said ejector element being disposed across the coin passage to isolate the remaining portion of the coin passage as the coins are being forced from the said length thereof.

10. In a coin changer of the character described, a case having a coin passage formed therein; an operating handle; a coin ejector; and means interconnecting the handle and said ejector for moving the same in a direction to force coins from the passage, said interconnecting means including at least two reciprocable superimposed slotted plates for the reception of coins of different denominations to be changed, one of said plates being connected to said handle, the other of said plates being joined to said ejector, the slots of said plates being in register and longer than the diameter of the largest coin to be changed, the length of the path of travel of the plate joined to said ejector being governed by the diameter of the coin received in the registered slots of the plates whereby the number of coins forced from the coin passage is controlled by the diameter of the coin to be changed.

11. In a coin changer of the character described, a case having a coin passage formed therein; an operating handle; a coin ejector; and means interconnecting the handle and said ejector, said coin passage being arranged to hold the coins in grouped, tandem, aligned relation in a common plane, said ejector being disposed to force a number of said coins from the end of the aligned group thereof.

12. In a coin changer of the character described, a case having a coin passage formed therein; an operating handle; a coin ejector; 70

and means interconnecting the handle and said ejector, said coin passage being arranged to hold the coins in grouped, tandem, aligned relation in a common plane, said ejector being disposed to force a number of said coins from the end of the aligned group thereof, said coin passage having an offset stretch of sufficient length to set off a part of the grouped, aligned coins, said ejector being positioned to act upon the coins in said set off group thereof.

13. In a coin changer of the character described, a case having a coin passage formed therein; an operating handle; a coin ejector; and means interconnecting the handle and said ejector, said coin passage being arranged to hold the coins in grouped, tandem, aligned relation in a common plane, said ejector being disposed to force a number of said coins from the end of the aligned group thereof, said coin passage having an offset stretch of sufficient length to set off a part of the grouped, aligned coins, said ejector being positioned to act upon the coins in said set off group thereof, said ejector serving to hold the coins in the remaining portion of the coin passage against displacement until at least a portion of those in offset stretch are forced therefrom.

14. In a coin changer of the character described, a case having a coin passage formed therein; an operating handle; a coin ejector; and means interconnecting the handle and said ejector, said coin passage being arranged to hold the coins in grouped, tandem, aligned relation in a common plane, said ejector being disposed to force a number of said coins from the end of the aligned group thereof, said coin passage having an offset stretch of sufficient length to set off a part of the grouped, aligned coins, said ejector being positioned to act upon the coins in said set off group thereof, there being a retaining finger mounted adjacent to and extending into the path of travel of the coins in said offset stretch of the coin passage to yieldably retain the coins therein.

15. In a mechanical coin changer of the character described, a case having a narrow vertical feed chamber formed to hold coins in edge-to-edge relation and in the same plane; a hopper for coins to be dispensed, said coins when in the hopper being in random condition; and apparatus for transferring coins from the hopper to said feed chamber and simultaneously arranging the transferred coins in said edge-to-edge relation, said apparatus for transferring the coins from the hopper to said feed chamber including a reciprocable slide; said slide having a transversely inclined edge disposed to direct coins laterally toward the feed chamber from the hopper as the slide moves through its path of travel.

16. In a mechanical coin changer of the character described, a case having a feed chamber and a coin passage formed therein; a hopper in communication with said feed chamber for coins to be dispensed, said coins when in the hopper being in a random condition; and coin controlled means for ejecting coins from the coin passage, said coin controlled means including an ejector element movable throughout a portion of the coin passage for forcing coins from said portion of the passage.
